CONTAINER SEALING MACHINE

Ralph M. Mero, Chicago, Ill., assignor to Continental Can Company, Inc., New York, N. Y., a corporation of New York

Application July 30, 1942, Serial No. 452,956

6 Claims. (Cl. 113—24)

This invention relates to container sealing machines and more particularly to machines of this class wherein means are provided for adjustably spacing a container supporting pad or the like and a cooperatively positioned container end supporting chuck to adapt and adjust the machine for sealing containers of different sizes.

Some machines of this class heretofore known in the art have included interengaging screw-threaded adjusting elements connected respectively to a container supporting pad and container end supporting chuck, the arrangement being such that relative rotation of the screw-threaded adjusting elements accompanied by relative longitudinal movement thereof serves to vary the spacing of the pad and chuck. An example of a previously known construction of this character is disclosed in the patent to Troyer et al. No. 1,891,851, granted December 20, 1932.

An object of the invention is to provide a machine of the general class referred to including an improved and simple means for locking the screw-threaded adjusting means in adjusted position.

Another object of the invention is to provide a machine of the character referred to in which locking of the parts in adjusted positions is accomplished by causing the threads of the adjusting members to bind upon one another.

A further object of the invention is to provide a container sealing machine of the kind referred to including a locking screw rotatable in unison with but movable axially with respect to one of the adjusting members and having threaded connection with the other of the adjusting members, means being provided for moving the locking screw axially with respect to its companion member to cause the interengaging threads of the adjusting members to bind.

Other objects of the invention will become apparent from a reading of the following description, the appended claims and the accompanying drawing.

In the drawing:

Figure 1 is a fragmentary vertical section showing screw threaded adjusting means for variably spacing a container supporting pad and container end chuck equipped with adjusting and locking means embodying the invention in a preferred form.

Figure 2 is a bottom plan view of a locking screw, and

Figure 3 is an elevation of the locking screw.

The drawing illustrating the invention in one form, shows only certain of the known parts of

container sealing machines of a known class in connection with which the invention may be embodied. The known parts shown include these with which novel means is cooperable for locking a container carrying pad and container end chuck in adjustably spaced relation.

Referring first to the generally known structure, a fixed frame part 1 carries two roller bearing assemblies 2 and 3 which journal a rotatable assembly including a center column 4 and a driving sleeve 5. The column 4 and sleeve 5 are keyed at 6 to rotate together but may be moved longitudinally with respect to each other.

A rotor 7 secured to the sleeve 5 by bolts, one of which is shown at 8, is formed with vertical guides for mounting a plurality of reciprocable pads adapted to support cans while being moved around the center column 4 for being sealed in any suitable manner. One of the guides is shown at 9 receiving a can supporting pad 10 equipped at its lower end with a roller 11 engaging a frame-mounted cam 12. When the sleeve 5 rotates the roller 11 will be moved vertically by the cam 12 to raise the can and the pad 10 to sealing position.

A seaming head 13 is secured to the center column 4 by a nut 14 and key 15 so as to rotate with and to be held in fixed position vertically with respect to the center column. The head 13 mounts a plurality of can end support chuck units disposed respectively above the pads 10 previously referred to, one of the chuck units being shown at 16. The chuck unit, shown as being provided with a knockout pad or ejector 17, may be operated by any suitable mechanism (not shown).

The sleeve 5 and center column 4 are rotated together by power supplied by a gear 18 driven by means (not shown). The gear 18 meshes with a ring gear 19 to which is attached a clutch member 20 held concentric with the sleeve 5 by a ball bearing assembly 21 anchored in a clutch member 22 keyed at 23 to the sleeve 5. A housing 24 secured to the clutch member 23 by bolts 25 is formed with pockets 26 receiving springs 27 which press an annular clutch member 28 against the bottom of the clutch member 20.

In operation, rotation of the gears 18 and 19 will drive the sleeve 5 through the clutch member 28, the housing 24 and the clutch member 22. A gear 29 keyed at 30 to the clutch member 22 meshes with a gear 31 which may be arranged to drive other mechanism (not shown) which is not part of the mechanism embodying the invention.

In order to condition the machine for receiving and sealing cans of different sizes, the center col-

umn 4 connected to the can end supporting chucks 16 and the sleeve 5 connected to the pads 10 are connected for relative vertical movement by inner and outer screw threaded adjusting means. In the form shown, a hollow adjusting screw 32 has threaded connection with internal threads 33 formed on the center column 4 and is mounted at its lower end in a bearing assembly 34 carried by the housing 24. The bearing assembly 34 permits rotation of the screw 32 within the housing but prevents relative longitudinal movement between the screw and housing. Non-reversible mechanism for rotating the adjusting screw 32 relative to the column 4 may be similar to mechanism disclosed in the patent to Troyer et al. No. 1,891,351, previously referred to. As shown a worm wheel 35 keyed at 36 to the adjusting screw 32 meshes with a worm 37 journaled in the housing 24. A square end 38 on the worm 37 is adapted to receive a socket wrench or suitable socketed handle by which the worm may be turned to rotate the worm wheel and the adjusting screw 32 so as to effect the desired adjustment.

In operation, the sleeve 5 with the parts connected thereto including the pads 10 and the center column 4 with the parts connected thereto including the chucks 16, will rotate together.

In accordance with the present invention, releasable means are provided for locking the screw-threaded adjusting means 32-33 in adjusted position so as to maintain the pads 10 and chucks 16 properly positioned to handle cans of the size for which the machine is adjusted. In the preferred embodiment of the invention, a locking screw 39 has threaded connection with the threads 33 of the center column 4. The screw 39 is formed with a projection having a non-circular portion 40 which extends into a correspondingly shaped recess 41 in the upper end of the adjusting screw 32. The locking screw 39 is thus constrained against rotation with respect to the adjusting screw 32 but the clearance between the projecting portion 40 and the recess 41 is sufficient to permit relative axial or longitudinal movement between the screws 32 and 39.

A rod or bolt 42 has a reduced upper end portion 43 extending coaxially through the locking screw 39 to which it is keyed as at 44. A nut 45 screw-threaded on the projecting end of the reduced portion 43 holds the locking screw 39 tightly against a shoulder at the juncture of the reduced portion 43 of the rod and the rod proper. The rod extends down through the axial opening in the adjusting screw 32 and through an opening 46 in a cap 47 secured to the housing 24 by screws 48. The lower end portion 49 of the rod is threaded to receive a releasable clamping nut 50 which can be tightened against the abutment provided by the cap 47 to draw the locking screw and adjusting screw relatively together.

The clamping means is operable during engagement of the screw threaded adjusting means 4 and 32 with each other and during engagement of the locking screw 39 with the threads 33 of the column 4 selectively for exerting a force urging the locking screw 39 axially with respect to the adjusting screw 32 to effect binding between the threads of the screw 32 and the threads 33 on the column 4; or for discontinuing the exertion of such force so as to discontinue substantially completely the binding between the threads of the adjusting screw 32 and the threads 33. Thus, when it is desired to rotate the screw 32 relatively to the center column 4 for adjust-

ing the chucks 16 vertically with respect to the pads 10, the clamping nut 50 is loosened and the worm 37 is turned to rotate the adjusting screw 32 relatively to the center column 4. While the adjusting screw is being rotated the locking screw 39 will turn with it freely in contact with the center column threads 33. In order to lock the parts in adjusted positions, the nut 50 is tightened, thus pulling the rod 42 downwardly and drawing the adjusting screw 32 and locking screw 39 relatively towards each other. This will cause the threads on the screws 32 and 39 to bind against the center column threads 33, thereby securing the center column 4 and adjusting screw 32 against relative turning.

The construction disclosed herein embodies the invention in the now preferred form but it will be understood that changes may be made without departing from the invention as defined in the claims.

I claim:

1. In a machine for sealing cans, means for supporting a can, means for supporting a can end in cooperative position relative to a supported can, two interengaging screw-threaded adjusting means connected to said can end supporting means respectively for variably spacing said two supporting means from each other, screw-threaded locking means rotatable in unison with and movable axially with respect to one of said screw-threaded adjusting means and having threaded connection with the other of said screw-threaded adjusting means, and releasable means including a manipulatable element positioned to be accessible at a point remote from said screw-threaded locking means and being adjustable during engagement of said screw-threaded adjusting means with each other and during engagement of said screw-threaded locking means with said other of said screw-threaded adjusting means for selectively exerting a force urging said screw-threaded locking means axially with respect to said one of said screw-threaded adjusting means 40 to effect binding between the threads of said two screw-threaded adjusting means or for discontinuing the exertion of said force to thereby discontinue substantially completely the binding between the threads of said screw threaded adjusting means.

2. In a machine for sealing cans, means for supporting a can, means for supporting a can end in cooperative position relative to a supported can, two interengaging screw-threaded adjusting means connected to said can supporting means and to said can end supporting means respectively for variably spacing said two supporting means from each other, screw-threaded locking means rotatable in unison with and movable axially with respect to one of said screw-threaded adjusting means and having threaded connection with the other of said screw-threaded adjusting means, means constraining said screw-threaded locking means to rotate in unison with said one of said screw-threaded adjusting means, and clamping means including a manipulatable element positioned to be accessible at a point remote from said screw-threaded locking means and being adjustable for releasably drawing said one of said screw-threaded adjusting means and said screw-threaded locking means axially towards each other.

3. In a machine for sealing cans, means for supporting a can, a means for supporting a can end in cooperative position relative to a sup-

ported can, two interengaging screw-threaded adjusting means connected to said can supporting means and to said can end supporting means respectively for variably spacing said two supporting means from each other, screw-threaded locking means rotatable in unison with and movable axially with respect to one of said screw-threaded adjusting means and having threaded connection with the other of said screw-threaded adjusting means, means constraining said screw-threaded locking means to rotate in unison with said one of said screw-threaded adjusting means, and clamping means for releasably drawing said one of said screw-threaded adjusting means and said screw-threaded locking means axially towards each other, said clamping means including a fixed abutment, a rod anchored to said screw-threaded locking means and extending therefrom parallel to the axis of said two screw-threaded adjusting means and having a portion projecting through and beyond said abutment and a nut having threaded connection with the projecting portion of said rod and engaging said abutment.

4. In a machine for sealing cans, means for supporting a can, means for supporting a can end in cooperative position relative to a supported can, two interengaging screw-threaded adjusting means connected to said can supporting means and to said can end supporting means respectively for variably spacing said two supporting means from each other, means for effecting relative rotation of said two screw-threaded adjusting means, screw-threaded locking means rotatable in unison with and movable axially with respect to one of said screw-threaded adjusting means and having threaded connection with the other of said screw-threaded adjusting means, and releasable means including a manipulatable element positioned to be accessible at a point remote from said screw-threaded locking means and being adjustable during engagement of said screw-threaded adjusting means with each other and during engagement of said screw-threaded locking means with said other of said screw-threaded adjusting means for selectively exerting a force urging said screw-threaded locking means axially with respect to said one of said screw-threaded adjusting means to effect binding between the threads of said two screw-threaded adjusting means or for discontinuing the exertion of said force to thereby discontinue substantially completely the binding between the threads of said screw-threaded adjusting means.

5. In a machine for sealing cans, means for supporting a can, means for supporting a can end in cooperative position relative to a supported can, inner and outer interengaging screw-threaded adjusting means connected to said can

supporting means and to said can end supporting means for variably spacing said two supporting means from each other, said inner screw-threaded adjusting means being formed with an axial opening, an abutment, means connecting said abutment to said inner screw-threaded adjusting means and maintaining said abutment and said inner screw-threaded adjusting means against relative movement axially of said inner screw-threaded adjusting means, a locking screw having threaded connection with said outer screw-threaded adjusting means, means connecting said locking screw to said inner screw-threaded locking means to rotate in unison therewith and to be movable axially relatively thereto, a clamping rod connected to said locking screw and extending through said axial opening and projecting through and beyond said abutment, and releasable clamping means cooperable with said abutment and the projecting end of said rod for forcing said rod axially relatively to said inner screw-threaded adjusting means to thereby effect relative axial movement between said locking screw and said inner screw-threaded adjusting means with resultant effecting of binding between the threads of said two screw-threaded adjusting means.

6. In a machine for sealing cans, means for supporting a can, means for supporting a can end in cooperative position relative to a supported can, an internally threaded member connected to said can end supporting means, an externally threaded adjusting screw connected to said can supporting means and having threaded engagement with said internally threaded member, means for rotating said adjusting screw for effecting relative axial movement between said internally threaded member and said adjusting screw, an abutment, means connecting said abutment to said adjusting screw to maintain said abutment and said adjusting screw against relative movement axially of said adjusting screw, a locking screw having threaded engagement with said internally threaded member, means connecting said locking screw to said adjusting screw to rotate in unison therewith and to be movable axially relatively thereto, a clamping rod connected to said locking screw and extending axially through said adjusting screw and through said abutment and having a threaded end projecting beyond said abutment, and a clamping nut on the threaded end of said rod releasably screwed against said abutment for drawing the rod axially to move said locking screw relatively to said adjusting screw and to thereby effect binding between the threads of said internally threaded member and said adjusting screw.

RALPH M. MERO.
